UNITED STATES PATENT OFFICE.

LOUIS N. D. WILLIAMS, OF OGONTZ, PENNSYLVANIA.

HOSIERY.

1,184,500.

Specification of Letters Patent. Patented May 23, 1916.

Application filed June 23, 1914. Serial No. 846,711.

To all whom it may concern:

Be it known that I, LOUIS N. D. WILLIAMS, a citizen of the United States, residing in Ogontz, Pennsylvania, have invented 5 certain Improvements in Hosiery, of which the following is a specification.

One object of my invention is to produce an article of hosiery having a foot of less diameter than the leg, another object is to 10 provide a different character of web in the sole portion of the foot from that in the instep portion of the same, and still another object is to provide the foot with a toe of a shape similar to that shown in the patent 15 of Samuel Henshall, No. 388,678, dated August 28, 1888, but capable of quicker production than the patented toe.

In the accompanying drawings—Figure 1 is a view of the lower portion of a stocking 20 blank made in accordance with my invention; Fig. 2 is a similar view illustrating a different form of leg from that shown in Fig. 1; Fig. 3 is a view illustrating a stocking blank having its foot narrowed in accordance with my invention but having a 25 different type of toe from that shown in Fig. 1; Figs. 4 and 5 illustrate the feet and ankle portions of articles of hosiery having my invention embodied in the toe portion 30 but not in the foot of the stocking, and Fig. 6 is a diagram illustrating the arrangement of the needles in a circular knitting machine intended for the production of articles of hosiery in accordance with my invention. 35

In carrying out my invention I use a machine of a special type, such as shown in an application for patent filed by me of even date herewith, this machine having two 40 banks of needles 1 and 1^a, as shown in Fig. 6, and two independent and separably operable cam cylinders, one for acting upon one bank of needles and the other for acting upon the other bank, as set forth, in the 45 application before alluded to.

The cam cylinders may be reciprocated so that to-and-fro knitting may be simultaneously performed upon both banks of needles, the needle actuating cams of one 50 cylinder being diametrically opposed to those of the other cylinder, or the cylinders may be adjusted so that the cams of one may follow those of the other in their action in order to produce continuous tubular 55 web by round-and-round knitting, and each cam cylinder is combined with picking de-

vices whereby needle after needle may be raised out of operative relation with the knitting cams in order to gradually narrow the webs produced during to-and-fro 60 knitting, and either or both of the cam cylinders may also be combined with picking devices whereby the needles first raised out of action may subsequently be restored to action again in order to gradually widen 65 the previously narrowed web, and thus form heel or toe pockets in the ordinary manner.

In producing a stocking of the character shown in Fig. 1, round-and-round knitting upon all of the needles of the machine may 70 be commenced at the upper portion of the leg and continued down to the beginning of the heel, whereupon rotary knitting is discontinued, the further production of web being by to-and-fro knitting upon each 75 bank of needles independently of the other and with independent yarn for each bank of needles. While the bank of needles 1 is inoperative the heel α is produced with one yarn upon the bank of needles 1^a, the web 80 being first narrowed and then widened again to form the heel pocket extending to the line α , whereupon reciprocating or to-and-fro knitting upon both banks of needles is started, the needles 1^a being supplied with 85 one yarn and the needles 1 with a different yarn.

Needle after needle first at one end and then at the opposite end of each bank is then withdrawn from action so as to narrow the 90 webs until the line γ is reached, any desired number of needles being thus withdrawn and any desired number of courses of 95 stitches knitted during this operation so as to produce on each web narrowing gussets of the desired contour. For instance, supposing that there are one-hundred and ten (110) needles in each bank, five (5) needles at each end of each bank may be withdrawn from action so that only one-hundred (100) needles of each bank will remain in action 100 for the formation of the foot, hence if the leg of the stocking contains two-hundred and twenty (220) wales of stitches the foot will contain only two-hundred (200) wales, one-hundred (100) in the sole portion and one-hundred (100) in the instep portion. 105

Reciprocating knitting with one yarn upon the one-hundred needles of bank 1^a to produce the sole web α' , and with another 110 yarn upon the one-hundred needles of bank 1 to produce the instep web β' is then con-

tinued until the point is reached at which the toe is to be formed and during this knitting period I prefer to produce a more closely knitted web in the sole portion of 5 the stocking than in the instep portion, this object being attained by drawing shorter stitches on the sole producing needles 1^a than upon the instep producing needles 1 and by increasing the number of courses in the sole 10 as compared with the number of courses in the instep, for instance, while the instep portion may have between the line y and the beginning of the toe, one-hundred (100) courses the sole portion between the same 15 lines may have one-hundred and fifty (150) courses.

In producing the toe two tapering webs are knitted, one constituting a continuation a² of the sole portion a' of the foot and the 20 other a like continuation b² of the instep portion b' of the foot, these webs being tapered by gradually lifting out of action, successively, first at one end and then at the opposite end of the set, needle after needle 25 until the desired narrowing has been effected, the stocking being completed by uniting the edges c—c', c'—c', d—d, and e—e, by sewing, looping, or in any other available way.

30 The union of the edges c'—c' and e—e is preferably effected in the following manner: Upon the completion of the narrowed webs a² and b² the stitches from all of the needles of both banks 1—1^a are transferred 35 to the points of a looping machine and looped together in the ordinary manner, thus uniting said edges c'—c' and e—e without casting the stitches from the needles and therefore without risk of running back of 40 the stitches on the edges c'—c' and e—e, during the handling of the stocking subsequent to such casting off of the stitches and before uniting said edges c'—c' and e—e, a further advantage being that by this method 45 said edges can be united without the formation of any objectionable seam. This operation having been completed the edges c—c and d—d are then united in any desired way in order to complete the formation of the 50 foot of the stocking.

Another method of uniting the edges c'—c' and e—e which may be adopted is to first complete the formation of the narrowed webs a' and b' and then to form one 55 or more continuous courses of stitches on the needles of each bank 1 and 1^a either by independent to-and-fro knitting upon the needles of each bank or by round-and-round knitting upon the needles of both banks, 60 the stitches of one of these courses being then united by looping or otherwise so as to join the edges c'—c' and e—e, and said courses being then severed at a point between the edges c'—c' and e—e so as to permit of the extension of the foot and instep 65

webs and bringing together of the selavage edges d—d of the same for subsequent joining.

The stocking blank shown in Fig. 2 is similar to that shown in Fig. 1, with the 70 exception that it is produced entirely by to-and-fro knitting upon the separate banks of needles, the front and rear webs in the leg portion of the stocking being united along the line f, preferably by a line of suture 75 stitches produced during the knitting operation.

The stocking blank shown in Fig. 3 is produced in the same manner as that shown in Fig. 1 until the formation of the toe is 80 reached, whereupon instead of forming narrowed webs, one projecting from the instep portion of the foot and the other from the sole portion of the same, a toe pocket g similar to the heel pocket a is formed upon the sole portion of the web by first narrowing and then widening the web produced by to-and-fro knitting upon the bank of needles 1^a, the edge h of this toe pocket being united to the forward edge h' of the instep web b', 90 either independently or as part of the operation which includes the uniting of the edges d—d.

The stocking shown in Fig. 4 is not narrowed in the foot portion, both leg and foot 95 being produced by round-and-round knitting upon all of the needles of both banks 1 and 1^a, and the stocking having the usual seamless heel a produced by to-and-fro knitting upon the needles 1^a. The toe is produced by simultaneous to-and-fro knitting 100 upon the needles 1 and 1^a independently and with independent yarns, the toe webs being shaped by narrowing in the same manner as in producing the toe shown in Figs. 1 and 2. 105

The stocking shown in Fig. 5 is produced in the same manner as that shown in Fig. 1, with the exception that the foot is not narrowed, the sole and instep webs being produced by simultaneous to-and-fro knitting 110 independently and with separate yarns upon the full number of needles 1 and 1^a, and being united along each side of the foot by a line of stitches p, preferably suture stitches, produced during the knitting operation. 115

I claim:—

1. A stocking having a foot composed of independently knitted instep and sole webs and a seamless heel integral with said sole web and with the rear of the leg, said sole web being knitted with shorter stitches than the instep web and having between the heel and toe a greater number of courses than the instep web. 120

2. The mode herein described of producing a stocking foot, said mode consisting in knitting to-and-fro simultaneously upon oppositely disposed banks of needles, supplying one yarn to one bank of needles and another yarn to the other bank of needles, 125 130

knitting continuously upon a given number of needles in each bank to produce instep and sole webs, and then putting out of action, at the opposite ends of each bank, 5 needle after needle in succession so as to narrow said webs to form the toe.

3. The mode herein described of producing a stocking foot, said mode consisting in knitting to-and-fro simultaneously upon oppositely disposed banks of needles, putting out of action, at the opposite ends of each bank, needle after needle in succession so as to narrow the webs, then knitting to-and-fro in the same manner upon the remaining 10 needles of each bank to produce instep and sole webs of the desired length, and then putting out of action at the opposite ends of the active banks of needles needle after needle in succession so as to narrow the webs 15 at the toe.

4. The mode herein described of producing a stocking foot, said mode consisting in knitting to-and-fro simultaneously upon oppositely disposed banks of needles, supplying one yarn to one bank of needles and another yarn to the other bank of needles, putting out of action, at the opposite ends of each bank, needle after needle in succession so as to narrow the webs, then knitting to- 20 and-fro in the same manner upon the remaining needles of each bank to produce instep and sole webs of the desired length, and then, while continuing such knitting, putting out of action, at the opposite ends of the active banks of needles, needle after needle in succession so as to narrow the toe 25 webs.

5. The mode herein described of produc-

ing a stocking foot, said mode consisting in knitting to-and-fro upon one of a pair of 40 oppositely disposed banks of needles, putting out of action at the opposite ends of said bank needle after needle in succession, and then reintroducing said needles in reverse order so as to form a seamless heel 45 pocket on said bank of needles, then knitting to-and-fro simultaneously upon the oppositely disposed banks of needles, supplying one yarn to one bank of needles and a different yarn to the other bank of needles 50 until the desired length of foot webs has been produced; and then putting out of action, at the opposite ends of each bank, needle after needle in succession, so as to narrow the webs for the production of the 55 toe.

6. The mode herein described of producing the foot portion of a stocking, said mode consisting in knitting to-and-fro simultaneously upon oppositely disposed banks of 60 needles, supplying one yarn to one bank of needles and another yarn to the other bank of needles, drawing shorter stitches upon one bank of needles than upon the other, and producing a greater number of courses 65 of stitches upon the needles drawing the short stitches than upon the needles drawing the longer stitches.

In testimony whereof, I have signed my name to this specification, in the presence of 70 two subscribing witnesses.
